UNITED STATES PATENT OFFICE.

THEODATUS G. BEEDE, OF YOUNGSTOWN, OHIO.

CARBURETER FOR GAS-ENGINES.

1,272,895.

Specification of Letters Patent. Patented July 16, 1918.

Application filed March 21, 1917. Serial No. 156,273.

To all whom it may concern:

Be it known that I, THEODATUS G. BEEDE, citizen of the United States, residing at Youngstown, in the county of Mahoning and State of Ohio, have invented certain new and useful Improvements in Carbureters for Gas-Engines, of which the following is a specification.

This invention relates to a carbureter for gas engines. The principal object of the invention is to provide an improved form of carbureter wherein I have provided a primary jet cap located immediately above a needle valve in combination with a fuel intake portion of carbureters.

Other objects and novel constructions of my carbureter are set forth in detail and claimed in combination with other parts of the carbureter.

With the above and other objects in view the invention consists in general of certain novel features of construction, combinations, and arrangements of parts as will be herein-after fully described, illustrated in the accompanying drawing and specifically claimed.

In the accompanying drawings like characters of reference indicate like parts in the several views, and:—

Figure 1 is a vertical median section through a carbureter constructed in accordance with this invention.

Fig. 2 is an enlarged vertical median section through the primary jet portion of the carbureter.

Fig. 3 is a top sectional view taken on the line A—A of Fig. 2.

Fig. 4 is a vertical median section through the secondary jet of the carbureter.

Fig. 5 is a top plan view of the cover plate covering the float chamber and fuel bowl.

The body of the carbureter comprises a bowl-shaped fuel bowl and float chamber 1. Within said chamber 1 is located an ordinary circular float 2 which is attached to a float lever 3 by means of a screw 4. This float lever 3 is pivoted at point 5 by being firmly attached to the wall of a side projection 6 of the above described chamber 1.

The other end of the float lever 3 is hinged to the upper end of valve stem 7. When the fuel in the bowl fills to a desired depth a valve 8 is forced downwardly into an intake fuel channel 9 thereby cutting off temporarily the fuel coming from the intake pipe

10 until such a time as the fuel in said chamber 1 is sufficiently lowered to cause the float 2 to open the valve 8.

The aforesaid chamber 1 is fitted with a circular cover plate 11 provided with a venturi 12 formed in the circular cover plate 11 at its central portion. This venturi 12 has a circular flange-shaped projection 13 being a portion of the venturi 12. The greater portion of the venturi 12 extends below the cover plate 11. This venturi 12 is funnel-shaped having the smaller diameter at its bottom. The lower portion of the venturi 12 extends a slight distance over a primary jet cap 14. This primary jet cap 14 is a circular cap which is threaded to the extended wall of a needle jet casing 20. This cap is provided with a central bore forming an air chamber 30. In this primary jet cap 14 immediately above a needle 22 a number of channels 32 radiate to the circumference of the needle cap 14 through which the atomized fuel is drawn.

On the lower side of the cover plate 11 is formed a circular flange 15 provided with threads on its inner surface into which is threaded a cone-shaped air chamber 16, the base of said air chamber 16 being provided with a circular downwardly extending portion 17 having a circular channel 18 extending through its central portion. The upper portion 19 of said channel 18 is greater in diameter than the remainder of said channel 18. Into this channel 19 is inserted a circular needle jet casing 20 having a flange 25 provided with a center bore 21 into which extends a needle 22 extending upwardly in the center bore 21. The needle jet casing 20 is securely held against a seat 23 by being threaded into the upper portion of the channel 18 at point 24. The flange 26 in turn is fitted against the bottom 27 of the air chamber 16.

Radiating from the air chamber 19 is a channel 28 turning downwardly at right angles near the circumference of the circular portion 17. Through this channel 28 air is taken into the air chamber 19 and then through holes 29 of the extended walls of the needle jet casing 20 allowing the air to pass into an air chamber 30 having a dome-shaped top with an opening 31 surrounding the upper portion of the needle jet casing 20.

In operation the air passes into the channel 28 then into the air chamber 19 then through the channels 29 into the air cham-

- ber 30. The fuel enters from the intake channel 31 and is drawn upwardly through the chamber 21 surrounding the needle 22 where the fuel and air undergo an atomizing process within the cap 14 which is threaded to the extended wall of the needle jet casing 20. This cap is provided with a central bore forming the air chamber 30. Immediately above the needle 22 a number 10 of channels 32 radiate to the circumference of the needle cap 14 through which the atomized fuel is drawn. The partially atomized fuel then passes upwardly through the venturi 12 being again mixed by air 15 from the air chamber 16, the air entering said chamber 16 by holes 33 which are located around the upper portion of the venturi 12 and which extend through the circular cover plate 11. See Figs. 1 and 5.
- 20 The fuel mixture is drawn up through the auxiliary air valve 34 which consists of a round wire coil spring the walls of which extend toward the top and which is firmly fastened at the bottom to the circular 25 flaring flange 13. At the top this auxiliary air valve 34 is attached within a circular band 35 whose circumference slides within a supply pipe 36 so that when the suction is increased or decreased the auxiliary air 30 valve 34 will allow air and fuel to enter between the coils in accordance with the degree with which the fuel is drawn into the supply pipe 36.
- The circular downwardly extending portion 17 of the air chamber 16 at its lower 35 end passes through an opening centrally located in the bottom of the fuel bowl and float chamber 1. The flange 37 fits into a seat 38 and is firmly held in position by 40 means of a lock nut 39. The needle 22 is provided with a threaded lower end 40 which threads into the lower end of the channel 18.
- A gland 41 fits around the wall 42 in 45 which the lower portion 40 of the needle 22 is threaded. When it is necessary to feed more fuel I have arranged a secondary jet 43 which consists of a tube extending through the circular cover plate 11 near the 50 inner side of the inner wall of the fuel bowl and float chamber 1. This secondary jet 43 consists of a tube with an adjusting screw 44 which is manipulated by means of a wheel 45. See Figs. 4 and 5.

The air chamber 46 is fastened to the top of the fuel bowl and float chamber 1 by means of screw 47. A strangle valve 48 is located within an air intake pipe 49. A throttle valve 50 is located within the supply pipe 36 and is controlled by a throttle lever 51. The carburetor is attached to the intake pipe 10 by means of a coupling 52.

There has thus been provided a simple and efficient device whereby the fuel becomes more thoroughly carburized than by ordinary carburetors and thereby resulting in greater economy of fuel.

It is obvious that many minor changes may be made in the form and construction of this invention without departing from the material principles thereof, and it is therefore not wished to confine the invention to the exact form herein shown, but it is wished to include all such as properly come within the scope of the appended claim.

What I claim as new is:

In a carburetor, the combination of a primary jet located within an air chamber centered within a fuel bowl, a venturi located directly above said primary jet, an auxiliary air valve consisting of a closely wound wire coil spring attached to the upper portion of the venturi, a circular band slidably fitted within a supply pipe, the upper portion of the above described auxiliary air valve firmly fastened to the circular band, an air chamber surrounding said auxiliary air valve, a needle jet casing, a fuel inlet channel, for said needle jet casing, an air chamber surrounding the lower portion of said needle jet casing, an air channel connected to said air chamber, channels extending upwardly through the extended wall of the needle jet casing connecting the said lower air chamber with an upper air chamber which surrounds the needle jet casing at its upper portion, a primary jet cap provided with a circular inverted cup, channels radiating from said cup substantially as described for the purpose set forth.

In testimony whereof I affix my signature in the presence of two witnesses.

THEODATUS G. BEEDE.
